UNITED STATES PATENT OFFICE

157,402

PLATE OR SIMILAR ARTICLE

Earl W. Newton, Chicago, Ill.

Application April 5, 1948, Serial No. 145,523

Term of patent 14 years

(Cl. D44—15)

To all whom it may concern:

Be it known that I, Earl W. Newton, a citizen of the United States of America, and resident of Chicago, county of Cook, and State of Illinois, have invented a new, original, and ornamental Design for a Plate or Similar Article, of which the following is a specification, reference being had to the accompanying drawings, forming part thereof, in which—

Figure 1 is a top plan view, parts being illustrated by broken lines, of a plate or similar article showing my new design; and

Figure 2 is a vertical cross sectional view of the same taken on line 2—2 of Fig. 1.

The ornamentation shown is continued about the periphery of the plate.

I claim—

The ornamental design for a plate or similar article, substantially as shown and described.

EARL W. NEWTON.
